(57) **CLAIM**

The ornamental design for an earbud case as shown and described.

DESCRIPTION

1.1 is a front elevation view of the earbud case according to our design;

1.2 is a rear elevation view thereof;

1.3 is a left elevation view thereof;

1.4 is a right elevation view thereof;

1.5 is a top view thereof;

1.6 is a bottom view thereof;

1.7 is a front-right-top perspective view thereof;

1.8 is a rear-left-bottom elevation view thereof;

1.9 is a front-right-top perspective reference view thereof showing the earbud case in a closed position; and,

1.10 is a rear-left-bottom perspective reference view thereof showing the earbud case in a closed position.

The broken lines in the drawings show portions of the earbud case that form no part of the claimed design.

1 Claim, 10 Drawing Sheets
